UNITED STATES PATENT OFFICE.

AMON T. NOE, OF PARNASSUS, PENNSYLVANIA.

BLOWER.

No. 918,358.

Specification of Letters Patent.

Patented April 13, 1909.

Application filed December 19, 1907. Serial No. 407,103.

To all whom it may concern:

Be it known that I, AMON T. NOE, a resident of Parnassus, in the county of Westmoreland and State of Pennsylvania, have 5 invented certain new and useful Improvements in Blowers, of which the following is a specification.

The primary object of this invention is to provide for forcing a large volume of air under an effective pressure. I accomplish this by so arranging the inlet as to secure a maximum inflow, and by maintaining the inlet and outlet out of direct communication, so that an effective discharging pressure is 15 maintained on the air pocketed between any two blades all the while such blade-separating space is in communication with the outlet, none of the air under discharge escaping backwardly through the inlet, and hence 20 none of the discharging pressure is wasted.

In the accompanying drawings, Figure 1 is a side elevation of the blower, partly broken to show the interior thereof. Fig. 2 is a sectional view on line 2—2 of Fig. 1.

25 Referring to the drawings, 2 is the rim-like peripheral wall of the circular casing, and 3 is one side wall thereof which, in the embodiment here shown, is straight or flat with the blades in operative proximity thereto as they 30 are with rim 2. Rim 2 and wall 3 may be cast integral, with the rim enlarged to form outlet chamber 4 through which the air is forced.

35 5 is the circular head which, in the present embodiment, closes the open side of the casing opposite wall 3, being secured to rim 2 by screws 6. Secured to the central shaft 7 are the similarly curved radial blades 8, all so arranged that their convex faces move toward 40 and drive the air into the outlet 4. The portion of head 5 diametrically opposite outlet 4 is enlarged or bulged outwardly at 9 and provided with air inlet 10 to which a pipe 45 may be connected for drawing air from any desired source. The flat portion 11 of head 5 adjacent outlet 4 provides a close fit for the blades, such as is afforded by all portions of wall 3 and the rim excepting where the latter is interrupted by outlet 4. Hence, that portion 50 of the casing interior on the approach side of the outlet, between lines *a* and *b*, comprises a space in which all edges of each blade have a working fit, so that when a blade is passing therethrough no air can escape 55 from its front or convex side to its rear or concave side and to the inlet, all the air being

driven forward positively toward the outlet. After passing outlet 4 the blades similarly fit the casing interior between lines *c* and *d*, the space being of such area and the blade-separating spaces so proportioned that no such space can at once communicate with the blower inlet and outlet. 60

Inlet enlargement 9 communicates at the same time with the inner portions of several 65 of the blade-separating spaces, or those portions nearest shaft 7, the most effective point of suction, so that a maximum volume of air is drawn inward. With the inlet and outlet completely separated, all of the air is 70 driven forward into the outlet under an effective pressure, there being no opportunity for any of it to escape backwardly to the outlet as would be the case if the inlet and outlet were in direct communication. 75 The blower rotates at high speed, and by admitting the air to the blade-separating spaces inwardly from the outer ends of the blades, it is obvious that those spaces are more completely filled and are filled with a 80 greater volume of air and at less resistance than though the air were admitted at the periphery of the casing. A centrifugal force of considerable momentum is generated by the rapidly revolving blades which 85 tends to throw the air outwardly from the blade ends, and this action would retard the admission of air at any point along the periphery of the chamber. With the blade-separating spaces out of communication 90 with the air inlet while discharging, the full accumulation of centrifugal force is available for throwing the air in large volume and with much force into the outlet. Whereas, 95 if the discharging spaces were in communication with the inlet it is clear that the volume of air discharged and the force of the discharge would be greatly diminished.

While I have here shown and described the blower in its preferred embodiment, the 100 same may be varied without departing from the spirit and scope of the appended claims.

I claim:

1. A blower consisting of a casing having an outlet, a series of blades rotatable within the casing, the casing having an air inlet open to several of the blade-separating spaces adjacent the inner ends of the blades, the blades so fitting the casing and so spaced apart that no blade-separating space communicates simultaneously with the casing inlet and outlet. 105 110

2. A blower consisting of a circular casing having an outlet leading from its periphery, a series of blades rotatable within the casing on a central shaft, the interior of the casing forming the approach to the outlet and a portion thereof beyond the outlet being of such size that the blades closely fit the same when approaching the outlet and after passing the same, the casing having an air inlet 10 open to the inner portions of several of the blade-separating spaces, the blades so spaced apart that no blade-separating space communicates simultaneously with the casing inlet and outlet.
3. A blower consisting of a circular casing enlarged at its periphery to form an outlet, a series of correspondingly curved blades rotatable within the casing on a central shaft with the convex faces of the blades approaching the outlet, those portions of the casing interior at opposite sides of the outlet being of such size that the blades closely fit the same, one side of the casing having an air inlet communicating with the inner por-

tions of several of the blade-separating spaces, the curved blades being so spaced apart that no blade-separating space communicates simultaneously with the inlet and outlet.

4. A blower consisting of a circular casing having an outlet leading from its periphery, a series of blades rotatable within the casing on a central shaft, those portions of the casing interior at opposite sides of the inlet being of such size that the blades closely fit the same, a side wall of the casing having a lateral air-inlet enlargement on the opposite side of the blade shaft from the outlet with the inlet communicating with several of the blade-separating spaces, the blades being so spaced apart that the inlet and outlet are never in open communication.

In testimony whereof I affix my signature in presence of two witnesses.

AMON T. NOE.
